UNITED STATES PATENT OFFICE

FRED M. YOUNG, OF RACINE, WISCONSIN

AIR HEATER

Application filed May 2, 1929. Serial No. 359,902.

This invention relates to improved space heaters.

The main objects of my invention are to provide a space heater in which two heat transferring units of the same type shown in my copending application Serial No. 358,872, filed April 29, 1929, which issued as Patent No. 1,753,587, on April 8, 1930, may be employed for doubling the heating capacity of a unit space heater; to provide an improved construction and arrangement in space heaters, of the type which create a forced draft of heated air, for facilitating the circulation of heated air in opposite directions; to provide a duplex heat interchanger for allowing simultaneous employment of a pair of fan propellers on a single fan motor, one for impelling the heated draft of air in one direction, and the other for impelling a heated draft of air in another direction; to provide an improved air deflecting device for dividing air drawn between the units into two oppositely directed currents for maintaining the two propellers under substantially identical working conditions, and to impart a circular movement to the air divided between the two currents for avoiding the creation of eddy currents which normally result when the direction of movement of a current of air is suddenly changed; to provide an improved heat interchanger having communicative units for heating oppositely directed air currents, and to provide an improved mounting between said units for a fan motor.

In the accompanying drawing I have shown a specific embodiment of my invention, in which:

Fig. 1 is a top plan view.

Fig. 2 is an end elevation.

In general my improved heating unit consists of spaced heat interchangers of a thin wall type each comprising upper and lower header tanks and an intercommunicative heat transferring core. The heat interchangers are substantially identical in construction with that shown and described in the above copending application. The heat interchangers are positioned in substantially parallel planes, and are communicatively connected at their upper ends

of a bridge which is formed integral with the upper header tanks of the respective interchangers, and which is provided with an internal passage. The bridge is provided on its upper side with a heating medium inlet 55 which communicates with the passage in the bridge.

The lower header tanks of respective heat interchangers are communicatively connected by an outlet pipe which is provided with 60 a fitting for receiving a return pipe of a fluid heating system.

A fan driving means is detachably suspended from the bottom side of the bridge and is positioned substantially midway between the spaced heat interchangers. The shaft of the driving means extends substantially perpendicular to the vertical sides of the radiators, and it is provided at each of its ends with a fan propeller. The fan propeller of each end of the shaft is located in close proximity to the core of one of the heat interchangers, and is adapted to impel a current of air outwardly between the water tubes thereof. An electric motor or fluid turbine 75 may be employed for driving the fan propeller.

The air is drawn inwardly by the fan propellers into the space between the heat transferring cores and is then forced outwardly 80 as illustrated by the arrows in the drawing.

A deflector is provided for equally dividing the incoming air between the two heat transferring cores and for preventing the creation of eddy currents in the center portion of the space between the radiators which would normally tend to reduce the volume of air impelled outwardly by the fans. The deflector is mounted on the motor housing, is substantially annular in shape and comprises 85 converging concaved sides which impart a circular movement to the air, thereby preventing the creation of eddy currents which are normally produced when air impinges against planar surfaces.

In the form shown the improved space heater is provided with spaced heat interchanges, each comprising upper and lower header tanks 1 and 2, and an intercommunicative heat transferring core 3. The heat 100

transferring cores comprise a series of water tubes arranged in spaced relation for providing air passages through the core. Fins 4 extend transversely through the core 3 providing ample surface for facilitating rapid transfer of heat from the core to a current of air passing therethrough.

The upper header tanks 1 are communicatively connected by a passage in a bridge 5, 10 which is preferably formed integral with the upper header tanks. The lower header tanks 2 are communicatively connected by an outlet pipe 6. The bridge 5 is provided with a threaded aperture for receiving a supply pipe 7 of a fluid medium heating system and the outlet pipe 6, connected at its opposite ends to the lower header tanks 2 of the respective heat interchangers, is provided with a threaded aperture for receiving a return pipe 8 of a fluid medium heating system. By means of this construction steam, hot water or other fluid heating medium may be circulated through the spaced heat interchangers which are preferably connected in a 25 fluid medium heating system in parallel relation so that substantially equal quantities of heating medium are passed through each heat transferring core.

The improved space heater may be conveniently suspended from ceiling or other over head structure by attaching supporting rods, not shown in the drawing, to the plates 9, rigidly attached to the ends of the upper header tanks 1. These plates are provided 30 with apertures 10 by means of which the heater may be conveniently attached to the lower extremities of depending rods. The rods may, if desired, be threaded in apertures in the upper header tanks 1.

40 The lower side of the bridge 5 is provided with a substantially horizontal, machined surface which forms a mounting for a fan supporting bracket 11. The upper end of the supporting bracket 11 is provided with a 45 plate 12 having apertures therein for receiving bolts 13 which are threaded in apertures in the bridge 5. A heat insulating gasket 12' is located between the horizontal surface of the bridge 5 and the plate 12 for preventing conduction of heat from the bridge.

Air propelling means, preferably comprising an electric motor 14 rigidly secured to the lower end of the bracket 11, is located midway between the spaced radiators. The shaft of the motor 14 extends outwardly at both ends of the motor housing and each end of the shaft is provided with a fan 15 and 16 respectively. The fan propeller 15 on the 60 left-hand end of the motor shaft as viewed in Fig. 2, is formed to impel a current of air outwardly to the left through the core 3 of one heat interchanger and the fan 16 on the right hand end of the motor shaft is formed 65 to impel a current of air outwardly to the

right through the core of the other heat interchanger.

An air deflector 17 of substantially annular shape and comprising concaved, converging sides 17', is mounted on the outer periphery of the housing of the motor 14 for distributing the incoming air substantially equally between the two heat interchangers as shown by arrows in Fig. 2.

The vertical edges of each heat transferring core 3 are provided with side plates 18. The left-hand heat interchanger is provided with a plurality of air deflectors 19 adjustably mounted on the side plates 18 and extending transversely across the front thereof. These deflectors may be positioned at any desired inclination to direct the flow of heated air either upwardly or downwardly. The left-hand heat interchanger is provided with a plurality of substantially vertical air deflectors 20 pivotally mounted at their upper and lower extremities on the upper and lower tanks 1 and 2 respectively. These air deflectors may be adjustably positioned for suitably directing the current of heated air sidewise. Each heat interchanger of a unit may be provided with horizontal or vertical air deflectors and if desired one may be provided with horizontal air deflectors and the other with vertical deflectors, as 95 illustrated in the drawing.

Air is drawn into the space between the two radiators of the heating unit through the top and bottom of the device which are open and through the screens 21 and 22 mounted on the sides of the heating unit.

Although but one specific embodiment of this invention has been herein shown and described, it will be understood that numerous details of the construction shown may be altered or omitted without departing from the spirit of this invention, as defined in the following claims:

1. In a duplex heating unit spaced heat interchangers each comprising an upper and lower header tank and an intercommunicative heat transferring core, means communicative with the upper and lower header tanks respectively for facilitating the connection of said heat interchangers in a parallel arrangement in a fluid heating medium system, an air impeller between said heat interchangers comprising a motor and spaced propellers formed to impel air outwardly therethrough in opposite directions, and means on said motor for distributing incoming air equally between said heat interchangers.

2. In a heating unit of the class described, spaced heat interchangers each comprising an upper and lower header tank and an intercommunicative heat transferring core, means communicatively connecting the upper header tanks of each heat interchanger for facilitating the connection thereof in a fluid heating medium system in parallel rela- 130

tion, a fan suspended from said means between said heat interchangers comprising a fan propeller adjacent each core for propelling air outwardly therethrough, means communicatively connecting the bottom header tanks for returning the heating medium from the latter to said fluid heating medium system, and deflectors adjustably mounted on the outer side of one of said heat interchangers for directing the flow of air sidewise after it has been heated.

3. A device of the class described comprising spaced heating units having air passages therethrough, a bridge rigidly connecting said heating units at their upper ends, a support rigidly mounted on said bridge and depending between said units comprising a tubular structure having flaring ends, a fan comprising a motor and spaced propellers rigidly mounted on the bottom end of said support, and an air deflector on the housing of said motor for directing substantially equal amounts of air through said units respectively and comprising concaved sides for imparting a circular movement to the air to avoid the creation of eddy currents.

Signed at Chicago this 19th day of April 1929.
